UNITED STATES PATENT OFFICE.

PROSPER TÉTREL, OF PARIS, FRANCE, ASSIGNOR TO THE BIGELOW CARPET COMPANY, OF CLINTON, MASSACHUSETTS.

DESIGN FOR CARPET.

SPECIFICATION forming part of Design No. 11,613, dated January 20, 1880.

Application filed December 9, 1879. Term of patent 3½ years.

To all whom it may concern:

Be it known that I, PROSPER TÉTREL, of Paris, in the Republic of France, have invented a new and original Design for Carpet, of which 5 the following is a specification.

This invention relates to a new and original design for carpets, oil-cloths, and similar fabrics; and it consists of the new configuration and ornamentation of parts hereinafter more 10 fully pointed out and described.

The accompanying photographic illustration represents a face view of my new design.

On the background of the carpet are a series of groups, A B C.

15 A is one of the groups of figures. It is composed of a rectangular figure, *a*, partially overlaid with flowers and leaves and a diamond-shaped figure, *b*, formed of detached checkers. The lower part of figure *b* is concealed by figure *a*, which overlaps it, and flowers and leaves are also superposed on figure *b*.

B is another one of the group of figures. Group B is of irregular outline, and it is composed of overlapping square checkers or scales 25 *c*, all pointing in the same direction, with flowers and leaves covering part of the figure.

C is the third of the group. It is composed of a half-rhombus, *d*, with flowers superposed on the field of said rhombus, which, in turn, 30 is placed against and at right angles to a figure, *e*, having parallel sides and a pointed end.

G is a field inclosed by a duplicated arrangement of groups A B C—that is to say, it is formed between two groups, A A, at top and bottom, between two groups, B B, diagonally opposite each other at the sides, and two groups, C C, also diagonally opposite to each other, as shown.

H is a floral group within the field G and 40 between the duplicated groups A B C.

fff are three sprays of flowers branching upward from the floral group H, two of which form borders for the field G and connect the figures A B C, while the third spray traverses the field G.

The field G has a dark lower background, *g*, against which the lighter leaves of the flowers are distinctly seen, and its upper portion, *h*, is light, so that the darker leaves are seen distinctly against it, the outlines of the leaves forming the line of division between the portions *g* and *h* of the field G.

I claim—

1. The design for a carpet, consisting of the group A, composed of the rectangular figure *a* and diamond *b*, substantially as shown.

2. The design for a carpet, consisting of the group B, which is composed of square overlapping checkers or scales *c*, all pointing in one direction, substantially as shown.

3. The design for a carpet, consisting of group C, composed of figures *d* and *e*, substantially as shown.

4. The design for a carpet, consisting of the groups A B C, floral group H, and field G, substantially as shown.

5. The design for a carpet, consisting of the field G and floral groups H *fff*, the field G having two portions, *g* *h*, of different colors, the line of division being formed by the outlines of the leaves of groups H *fff*, substantially as shown.

The above description of my invention signed by me this 21st day of October, 1879.

PROSPER TÉTREL.
